DESIGN FOR A WINDOW WEDGE OR THE LIKE

Walter Grosser Smull, Trenton, N. J.

Application June 5, 1937, Serial No. 69,705

Term of patent 14 years

To all whom it may concern:

Be it known that I, Walter G. Smull, a citizen of the United States, residing at Trenton, in the county of Mercer and State of New Jersey, have invented a new, original, and ornamental Design for a Window Wedge or the like, of which the following is a specification, reference being had to the accompanying drawing, forming part thereof.

I claim:

The ornamental design for a window wedge or the like, as shown.

WALTER GROSSER SMULL.
